GASOLINE VAPOR AND AIR MIXING DEVICE

William S. Alvey and John M. Mikkelsen,
Philadelphia, Pa.

Application May 20, 1933, Serial No. 671,998

1 Claim. (Cl. 48—180)

Our invention relates to gasoline saving devices for use in connection with internal combustion motors and more particularly relates to a novel device for vaporizing gasoline, mixing gasoline with air, and injecting further air into the mixture after the gasoline has left a carburetor and before it has entered a manifold.

Our invention comprises a novel device, adapted for ready insertion between a carburetor and a manifold, which includes propellers and a propeller shaft, actuated by suction from the manifold, which shaft carries breaker blades for thoroughly vaporizing the gasoline and mixing it with the air coming from the carburetor together with means for injecting further air into the mixture after it has passed the breaker blades, which means may be controlled to go into action at a predetermined desired time.

An object of our invention is to provide a novel means for decreasing the gasoline consumption of internal combustion engines without decreasing the efficiency thereof as measured, in terms of "pick-up", starting ease, or low speed performance.

A more specific object of our invention is to provide a novel device for vaporizing more completely the gasoline as it comes from the carburetor, mixing it with the air and, after such vaporization and admixture, injecting thereinto at a predetermined time and automatically a further supply of air.

Another object of our invention is to provide means for automatically injecting air into the mixture of gasoline and air after it has come from the carburetor, thus decreasing the suction upon the carburetor and hence the amount of gasoline used.

Yet another object of our invention is to provide a means for accomplishing the above objects which may readily be installed on an internal combustion engine between the carburetor and the intake manifold.

Other objects and advantages of our invention will be apparent from the following specification, claim, and from the drawing in which:

Fig. 1 is a vertical section of an embodiment of my invention taken on the line 1—1 of Fig. 2;

Fig. 2 is a vertical section taken on the line 2—2 of Fig. 1; and

Fig. 3 is a plan view of the device illustrated in Figs. 1 and 2.

The device 5, which we will hereafter refer to as a mixing device, embodied in our invention, is adapted for insertion in position between a carburetor indicated at 10 and an intake manifold

indicated at 8, the two being of any desired and suitable type and properly connected respectively to a source of fuel supply and to the intake ports of the motor (not shown).

Referring now particularly to Figs. 1 and 2, the mixing device indicated generally at 5 comprises a tubular unit 6 having upper and lower flanges 6c and 6d carrying ears 6a and 6b respectively. Through the ears 6a bolts 7 may pass to connect the device 5 to the lower end of the intake manifold 8. Through the lower ears 6b other bolts indicated at 9 may pass by which the device is connected to the upper end of a carburetor 10. Since the lower ends of the manifold and of the carburetor are normally of standard sizes, only a sufficient number of different types of my devices need be manufactured to meet requirements of those sizes since the flanges upon our mixing device are adapted to fit existing manifold and carburetor shapes and sizes.

The tubular unit 6 with its flanges serves as a separator and connector between the manifold and the carburetor, carries internally breaker mechanism, and externally adjacent its upper end an automatic air injection valve. The breaker 25 mechanism comprises a cross member 11, preferably cast integrally with the unit 6, through which passes a fixed shaft 12 in axial alignment with the tubular unit 6 upon which is mounted a casting 13 carrying upper and lower propeller 30 blades 14 and 15 respectively and a pair of substantially rectangular breaker blades 16 disposed radially of the axis of the casting 13. The upper face of the cross member 11 carries a lower part of a ball bearing raceway 20 adapted to complementarily fit a raceway formed in the lower part of the casting 13 in which ball bearings 21 are provided and the upper end of the shaft 12 is threaded and carries thereon a nut 23 having part of a portion 24 of a raceway complementing 40 another portion 25 thereof on the upper end of the casting 13 for guiding and facilitating the movement of the casting 13 about the shaft 12. The nut 23 may be held in position as by the lock nut 26.

As is usual in internal combustion engines the mixture passing from the carburetor to the manifold is drawn upwardly by suction from the engine which suction varies directly as the speed of the engine. The current of gasoline and air from the carburetor to the manifold in this instance is utilized to cause the rotation of the casting 13 through the propellers 14 and 15. The breaker blades 16 thus are caused to rotate and

thoroughly vaporize and mix the gasoline and air coming from the carbureter.

In order to decrease the fuel consumption when the motor has been started while maintaining all the advantages of a rich mixture at the time the motor is being started we provide an automatic air injector 30 having a port 31 entering the unit 5 in a plane above that of the breaker blade 16. The injector may comprise a hollow casing having a threaded end 32, fitting complemental threads in the casting 5, through which the port 31 extends and may be somewhat enlarged as at 33 and externally threaded as at 34 adjacent its opposite open end to carry a hollow cap 35. The cap 35 may have perforations 36 in the outer end thereof and an axially aligned opening 37 through which passes the stem 38 of a valve 39. The stem 38 is held in place in the opening 37, in such a position that the valve will close the perforations 36, by expansion spring 40 within the casing 30 and hollow cap 35. The cap 35 may be screwed toward or away from the casing 30 to increase or diminish the effect of the spring 40 and thus control the moment at which the perforations 36 will be connected with the interior of the casing and hence with the mixing device since the suction from the intake manifold when it reaches a predetermined point will cause a partial vacuum within the hollow casing and the valve will be moved away from the perforations by the external air pressure.

In operation this tension preferably should be so regulated that the openings will remain closed when the engine is starting or at idling speed but upon increase in such speed the suction should be great enough to overcome the force of the spring and allow the entrance of air. In automobiles, this preferably should be at a driving speed of about 15 miles per hour in high gear, as it seems that it is at this rate that the device may be brought into operation without decreasing the pickup of the car or effecting the rate of acceleration.

Various modifications may be made in the above described embodiment of the invention without departing from the spirit and scope thereof as set forth in the following claim.

We claim as our invention:

A gas mixing device comprising a tubular member; a cross bar spanning one end of said member; a fixed post coaxially arranged with respect to said member; a unitary casting shaped to form propeller and breaker blades mounted on said post; a nut engaging the end of said post remote from said cross bar; and ball bearings between one end of said casting and said cross bar and between the other end of said casting and said nut, whereby said casting is rotatively supported at both ends on a post supported at one end only.

WILLIAM S. ALVEY.
JOHN M. MIKKELSEN.
